CLAIM

The ornamental design for the walking support handle, as shown and described.

DESCRIPTION

FIG. 1 is a perspective view of a walking support handle in accordance with the present design;

FIG. 2 is a right side elevational view of the walking support handle illustrated in FIG. 1;

FIG. 3 is a left side elevational view of the walking support handle illustrated in FIG. 1;

FIG. 4 is a front elevational view of the walking support handle illustrated in FIG. 1;

FIG. 5 is a rear elevational view of the walking support handle illustrated in FIG. 1;

FIG. 6 is a top plan view of the walking support handle illustrated in FIG. 1; and,

FIG. 7 is a bottom plan view of the walking support handle illustrated in FIG. 1.

The broken lines in the figures show elements of the article that form no part of the claimed design.
